UNITED STATES PATENT OFFICE.

FRED FRAZER, OF SYRACUSE, NEW YORK.

SNAP-HOOK.

SPECIFICATION forming part of Letters Patent No. 251,862, dated January 3, 1882.

Application filed December 7, 1881. (No model.)

To all whom it may concern:

Be it known that I, FRED FRAZER, a citizen of the United States, residing at Syracuse, in the county of Onondaga and State of New York, have invented certain new and useful Improvements in Snap-Hooks, of which the following is a specification.

My invention relates to certain improvements in that form of snap-hooks in which the parts are separately made and afterward put together without the use of any extraneous devices, as rivets, &c.; and it consists in certain changes in the form of the shank of the hook and the construction of the tongue, as will be hereinafter described.

In the accompanying drawings, forming part of this specification, Figure 1 is a perspective view of a snap-hook embodying my invention. Fig. 2 is a plan view of the hook and spring. Fig. 3 is a vertical central section, and Fig. 4 is a perspective view of the tongue.

Like letters represent corresponding parts in all the figures.

The hook A, shank B, and loop C for the attaching strap or chain are cast in one piece. At the one end of the shank I provide a recess or depression, a, in the heel thereof, and the back portion of this recess is open entirely through the body of the shank, and is provided with inwardly-projecting lugs b b, one on each side, which receive and hold the coiled spring c. Within the recess or cavity a are also cast projecting eccentric flanges d d, on each side, which support the tongue and act as bearings for the curved hooks thereon, as will be hereinafter described.

The coiled spring c is formed with two free ends, one long and one short one. The short end in the completed hook bears against the

under side of the back part of the hook and operates to hold it in a closed position, while the longer end rests in a recess in the shank of the hook, immediately in front of the cavity a. This cavity is cast excessively wide. The 45 spring is inserted with the lugs b b projecting inside the coils thereof, and then by closing the cavity the lugs are forced toward each other, forming a journal for the spring, which is held firmly in place.

The tongue D is formed with two rearwardly-projecting curved hooks, and is of such shape that it fits snugly between the walls of the recess. The hooks are curved downwardly, and when inserted in the cavity in the shank of the hook they rest on the eccentric flanges on the sides of the cavity, which form bearings for them, while the free ends of the curved hooks or lugs on the tongue project underneath and partly surround the lugs b b, and the coiled 60 spring lies in the recess between them. After the spring is in place the tongue is secured by inserting the curved hooks on the end thereof in the cavity underneath the lugs.

I am aware that it is not new to provide a 65 snap-hook with a coiled spring resting in a recess in the shank of the hook, and such I do not claim as my invention; but

What I claim is—

A snap-hook having its hook, loop, and 70 shank cast in one piece, with a cavity, a, having eccentric side flanges and inwardly-projecting lugs, a tongue, D, with downwardly-projecting curved hooks, and the coiled spring c, all constructed and adapted to operate substantially as set forth.

FRED FRAZER.
